SUPPORT STRUCTURE FOR SHELVES

Sidney W. Martin, Chicago, Ill.

Application May 25, 1953, Serial No. 356,958

3 Claims. (Cl. 248—243)

This invention relates to structures adapted for use in supporting shelves, hanger rods, etc., and more particularly to a structure adapted to be readily installed between vertically spaced kitchen cabinets.

Many kitchens are now provided with vertically spaced cabinets and it is well known that such cabinets are not conveniently located to permit ready removal or replacement of those kitchen utensils frequently employed in processing and serving food products. It is also apparent that the space between such cabinets could be utilized to store certain kitchen utensils. It is, therefore, an object of the present invention to provide a structure adapted to be mounted in the space between base and wall cabinets to support those utensils most frequently employed in kitchens.

Another object of the invention resides in the provision of an inexpensive support structure adapted to be readily mounted between and engaged to base and wall cabinets to support shelves, hanger rods, etc.

A further object of the invention resides in the provision of a support structure constructed to permit ready adjustment of the several parts to suit the space available between cabinets.

Another object of the invention resides in the provision of a support structure embodying spaced upright bracket supporting frames, each frame being extensible and provided at its ends with locking clips for insertion between a wall and vertically spaced cabinets.

Another object of the invention resides in the provision of a support structure in which each of the bracket supporting frames comprises a pair of frame members adjustable vertically relative to each other and secured in adjusted position by locking elements.

It is a further object of the invention to provide shelf-supporting brackets on the frame members, each bracket being adjustable to different positions on its related frame member.

This invention embodies other novel features, details of construction and arrangement of parts which are hereinafter set forth in the specification and claims and illustrated in the accompanying drawings, wherein:

Fig. 1 is a front elevational view illustrating a support structure for shelves, hanger rods, etc., embodying features of the invention.

Fig. 2 is a side elevational view of same.

Fig. 3 is a side elevational view illustrating a modified form of the invention in which each side frame member comprises telescopically engaged tubular members.

Fig. 4 is a transverse sectional view illustrating another modified form of the invention in which each side frame comprises telescopically engaged channel members.

Referring now to the drawings for a better understanding of the invention, and more particularly to Figs. 1 and 2 therein, the support structure is shown as comprising identical side frames 6—6 adapted to extend vertically in spaced parallel relationship along a wall 7 between vertically spaced wall and base cabinets 8 and 9, respectively.

2

Each side frame 6 is shown as comprising identical inner and outer frame members 11 and 12 formed from lengths of flat strip metal, the inner member having its lower end offset forwardly at 13 for engagement against the base cabinet 9, and the outer member having its upper end offset forwardly at 14 for engagement with the upper cabinet 8. The offset end portions 13 and 14 are formed with apertures adapted to receive screws 16 to secure the frame members to their related cabinets.

10 Upper and lower collars 17 and 18 are sleeved over the frame members 11 and 12 and formed with threaded apertures to receive screws 19a to clamp the members against relative movement. Mounting clips 19 and 21 are secured to the inner and outer frame members 11 and 12, respectively, by means of screws 22, the outer ends of the clips being disposed between the wall 7 and their related cabinets 8 and 9 to secure the side frames 6 against movement outwardly from the wall.

15 Each side frame 6 is provided with a shelf-supporting bracket 23 formed from a length of flat strip metal to provide a horizontal portion 24 and a vertical portion 25 adapted to be clamped in fixed position on the frame by means of a collar 26 sleeved over the frame members 11 and 12 and having threaded apertures to receive locking screws 27. A shelf 28 is supported at its ends upon the brackets 23—23 and is engaged against outward displacement therefrom by means of upturned end portions 29 formed on the brackets.

20 Each side frame 6 is also provided with a hanger rod supporting bracket 31 formed of flat strip metal offset intermediate its ends, one end of the bracket being clamped to the side frame by means of a collar 32 and a screw 33, and the other end of the bracket being disposed to clamp a hanger rod 34 against the front side of the side frame. The hanger rod is formed with suitable apertures 36 to receive hooks (not shown) for supporting kitchen utensils.

25 To install the support structure, the frame members 11 and 12 are moved to engage their respective clips 19 and 21 between the wall 7 and cabinets 8 and 9 and the screws 19 are tightened to clamp the frame members against relative movement. The brackets 23 and 31 are then secured in adjusted position on their respective side frames 6 and secured in fixed position by the collars 26 and 32 and screws 27 and 33.

30 In the event the cabinets are flush against the wall 7, the clips 19 and 21 may be omitted from the side frames and the latter may be secured to the cabinets by the screws 16.

35 Fig. 3 illustrates a modified form of the invention in which identical side frames 36—36 are shown as comprising inner and outer frame members 37 and 38 formed of metal tubing of different diameters whereby the inner member may be telescopically adjusted within the outer member and secured in adjusted position by means of a split collar 39 and screw 41.

40 Identical mounting clips 42 and 43 are provided at opposite ends of each side frame, each clip being preferably formed from a length of strip metal to provide U-shaped body portion 44, a vertical leg portion 46 and a horizontal leg portion 47. The body portions of the clips are slidably mounted within the ends of their related frame members, and the vertical leg portions 46 are disposed between the wall 7 and their related cabinets 8 and 9. If desired, the leg portions 47 may be formed with apertures to receive screws 48 for engagement with the cabinets.

45 An angle-shaped bracket 49 is provided on each side frame 36 to support a shelf 51, each bracket having a C-shaped clip 52 secured thereto snugly embrace the outer frame member 38, and each bracket being secured in

adjusted position on its related side frame by means of a split collar 53 and screw 54.

Fig. 4 illustrates another modified form of the invention in which each side frame 56 comprises inner and outer side frame members 57 and 58 of channel section, the inner member being slidably engaged within the outer member. This form of the invention is otherwise similar to the form heretofore described and illustrated in Fig. 3 in the drawings.

In each of the several forms of the invention herein shown and described, it will be noted that the side frames are adapted to be installed for use by merely moving the side frame members relative to each other to engage their respective mounting clips between a wall and the vertically spaced cabinets, and then locking the frame members and shelf brackets against movement relative to each other by means of the clamping collars and locking screws.

While this invention has been shown in several forms, it is obvious to those skilled in the art that it is not so limited, but is susceptible of various changes and modifications without departing from the spirit and scope of the claimed invention.

I claim as my invention:

1. In a support structure for shelves, side frames including interconnected side frame members adjustable longitudinally relative to each other, mounting clips provided at opposite ends of each side frame, and brackets provided on said side frames to support a shelf, said side frame members being formed from lengths of metal tubing telescopically engaged for longitudinal movement relative to each other, each mounting clip being generally U-shape to provide a pair of legs and a U-shaped loop portion snugly telescopically engaged within its related side frame member, one of said legs having an outer end portion offset from and parallel to its related side frame member, and the other of said legs having an end portion disposed in a plane normal to its related side frame.

2. In a support structure for shelves, side frames in-

cluding interconnected side frame members adjustable longitudinally relative to each other, mounting clips provided at opposite ends of each side frame, and brackets provided on said side frames to support a shelf, said side frame members being formed from lengths of metal of generally channel section telescopically engaged for longitudinal movement relative to each other, each mounting clip being generally U-shape to provide a pair of legs and a U-shaped loop portion snugly telescopically engaged within its related side frame member, one of said legs having an outer end portion offset from and parallel to its related side frame member, and the other of said legs having an end portion disposed in a plane normal to its related side frame.

3. In a support structure for shelves, side frames including interconnected side frame members adjustable longitudinally relative to each other, mounting clips provided at opposite ends of each side frame, and brackets provided on said side frames to support a shelf, said side frame members being formed from lengths of metal telescopically engaged for longitudinal movement relative to each other, each mounting clip being generally U-shape to provide a pair of legs and a U-shaped loop portion snugly telescopically engaged within its related side frame member, one of said legs having an outer end portion offset from and parallel to its related side frame member, and the other of said legs having an end portion disposed in a plane normal to its related side frame.
